(57) CLAIM

The ornamental design for a food pan collar, as shown and described.

DESCRIPTION

FIG. 1 is a top view of the food pan collar.

FIG. 2 is a bottom view of the food pan collar.

FIG. 3 is a side elevational view thereof, all four edge views being identical; and,

FIG. 4 is a perspective view of the food pan collar in place on a container.

In the drawings, the broken line showing of a container depicts environment and forms no part of the claim.
